EXTENSION KEY CHAIN

William H. Meeker, Rochester, N. Y., assignor to
Hickok Manufacturing Co., Inc., Rochester,
N. Y., a corporation of New York

Application November 14, 1949, Serial No. 126,954

3 Claims. (Cl. 24—3)

1

This invention relates to extension key chains. The extension key chain of the present invention is of a character so that the effective length of the chain can be extended when the user has the keys on the ring, which is at one end of the chain in his hand, as differing from prior key chains wherein the effective length of the key chain is constant and cannot be extended for utilitarian purposes.

The present key chain consists of a rather long length of flexible chain or the like having at one end the usual snap fastener to which a watch or other article can be detachably secured, and, at its other end, a key ring upon which keys are to be carried. The said length of chain having the snap fastener at one end and the key ring at the other, passes through a slide block and this slide block has attached to it a length of chain, preferably shorter than the first mentioned length of chain, and this shorter length of chain has at one end thereof a fastener for detachably securing the extension key chain, as a whole, to a trouser loop or other means to which it may be secured.

The extension key chain functions very simply in that the longer length of chain to which the snap hook is attached at one end and the key ring at the other end, may be pulled through the slide block and thereby lengthen the effective length of the chain with respect to the slide block, depending upon which end of the chain is pulled, which results in the chain intermediate its ends being slid through the slide block with which it is associated. Instead of sliding the chain through the slide block by pulling on either end of the chain, at opposite sides of the slide block, the chain on either side of the slide block may be held in the hand and the slide block itself slid along the length of the chain until the desired effective length of the chain at either side of the slide block is attained. So, it will be seen that the said longer length of the chain can be extended by pulling upon either end thereof and thus extending the effective length of the chain or the chain may be held stationary and the slide block moved on and relative to the chain and thus also extending the effective length of the chain.

The aforesaid brief description of the present extension key chain, therefore, differs the invention radically from prior key chains where complicated looped formations are resorted to and overlapping of the same or two or more chains are resorted to.

With the above in mind, it is an object of the invention to provide an extension key chain whereby the effective length of the key chain may be affected by either pulling one end of the chain to lengthen that end portion with respect to a slide block or to hold the said chain stationary and move or slide the slide block along the chain to accomplish an extension of the said chain.

2

Another object of the invention is to provide an extension key chain consisting of a tethered slide block and a rather long length of chain that is associated with the said slide block and which chain can be moved relative to the slide block or with the same and lengthen the said chain, or the slide block moved with or relative to the said chain.

Another object of the invention is to provide an extension key chain consisting of a flexibly tethered slide block and a key chain associated with the slide block and extending through a portion of the same and capable of being moved with or relative to the said slide block, and the said chain having on opposite ends thereof securing devices for attachment thereto of various articles such as watches, key rings, etc.

Another object of the invention is to provide an extension key chain consisting of a flexibly tethered slide block and a flexible key chain associated therewith and extending from opposite portions of the slide block, thereby disposing portions of the key chain outwardly of the slide block and the key chain being capable of being moved relative to or with the slide block and, likewise, the slide block being capable of movement relative to or with the said chain.

Another object of the invention is to provide an extension key chain consisting of a relatively few inexpensive parts that are capable of being quickly associated to form component elements constituting the extension key chain as a whole and which elements essentially consist of a flexibly tethered slide block and a length of chain associated with the slide block and capable of being slid through the slide block and the said chain having attaching devices at either end thereof.

With these and other objects in view, the invention consists in the construction and novel combination and arrangement of parts herein-after fully described, illustrated in the accompanying drawings and pointed out in the claims hereto appended, it being understood that various changes in the form, proportions, and minor details of construction, within the scope of the claims, may be resorted to without departing from the spirit of or sacrificing any advantages of the invention.

In the drawings:

Fig. 1 is a view of the extension key chain slightly in perspective, showing the chain in association with the trousers of the wearer;

Fig. 2 is a transverse sectional view taken substantially along the lines 2—2 of Fig. 1, looking in the direction of the arrows;

Fig. 3 is a vertical sectional view taken substantially along the lines 3—3 of Fig. 1, looking in the direction of the arrows;

Fig. 4 is a perspective view of one of the elements constituting the slide block and showing

a portion of the chain and its association with the same;

Figs. 5 and 6 are diagrammatic illustrations disclosing two ways of extending the key chain.

The invention will be more readily understood by referring to the several figures of the drawings in detail wherein like reference numerals in the several figures denote the same parts or elements.

The extension key chain consists of the slide block denoted generally at 6, which slide block has attached thereto a short length of chain 7 by means of the ring 8 at one end thereof and the other end of this chain has a detachable fastener 9 attached thereto. A longer length of chain 10, relative to the length of the chain 7, slidingly passes through a passageway herein-after described in the slide block hereinafter described, and this length of chain, at one end thereof, has secured thereto a key ring or the like 11, and has secured to its other end a conventional snap hook 12 which is of the type that is ordinarily adapted to be detachably secured to the loop of a watch or other such article. The key ring 11 may take the form as described in application, Serial No. 115,864, filed September 15, 1949, or may be a conventional key ring or the like, the key ring as disclosed in Patent 2,257,304, issued September 30, 1941, and, likewise, the fastener 9 may be identical with the fastener 41 disclosed in the said patent application or the fastener 1 disclosed in the said patent. Obviously different types of fasteners and key rings can be associated with the ends of the extension key chain 10 and a different form of snap hook or other fastener may be substituted for the snap hook 12.

The slide block denoted generally at 6 is substantially triangular shaped in outline but, of course, may well be of other shapes, contours and outlines. This slide block consists of two substantially similarly formed sections 13 and 14, and which sections may be made of plastic material, metal, alloys of metals, or any other suitable material and, as illustrated, the slide block is made of plastic. Each section of the slide block has downwardly diverging side walls at 15 and 16 at the upper portions thereof and, at the lower portions of each of the sections constituting the slide block, there are walls 17 and 18 converging toward the bottom 20, and which bottom is provided with a groove 21 and a similar groove 22 is provided in the top of the slide block, and which grooves communicate with a similarly formed groove 23 in each of the front faces 24 of the sections 13 and 14.

The inner face of section 13 of the slide block is provided with raised protuberances 25, preferably semi-spherical in shape, and which protuberances, when the two sections are brought together, rest in similarly formed semi-spherical recesses 26 and serve as a means to properly position the two sections 13 and 14 together during assembly and to maintain them in their properly adjusted positions with respect to each other when assembled together.

Each section 13 and 14 of the slide block is provided with a transversely extending arcuate channel or passageway 27, which passageway is semi-circular in cross section. When the two sections 13 and 14 are brought together and assembled, the passageway formed by the registering channels is substantially circular in transverse outline and arcuate longitudinally towards its ends 28 and 29. The passageway extends at a downward incline towards its open

ends, thus allowing the chain 10 to be readily slidably moved through the said passageway when pull is exerted upon the chain.

The slide block also includes spaced transversely semi-circular recesses 30 and 31 in each section thereof and a web 32 separating the two said recesses and this web having a circular cut-out central portion 33 which serves as a bearing for the friction plunger shaft 34 which has at one end thereof a convex head 35 and, adjacent the other end 36 thereof, there is a circular enlargement 37 which abuts against the upper portions of the webs of the two sections 13 and 14 in its downward movement, which is the normal position thereof, and which plunger is maintained in this position by means of a coil spring S that is mounted in the recesses 30 of the two sections. The convex head 35 is positioned in the recess 31 and is free to move therein under the resiliency of the spring S, and this recess 31 intersects the recesses 27 of the two sections midway the length thereof and partially projects into the passageway formed by the recesses 27 and is adapted to resiliently engage that portion of the chain in the channel immediately opposite the end of the said plunger in order to apply friction thereto, and to maintain the chain 10 in any adjusted or extended position.

The two sections 13 and 14 of the slide block, as aforesaid, are maintained in registry by the projections 25 fitting in the recesses 26 and these two sections are held together by a metallic or other bale 38 which is disposed in the aforesaid grooves 23 in the opposite outer faces of each section and, likewise, in the grooves 21 in the bottom of each of the sections and also in the grooves 22 in the top of each of the sections, and the ends of the bale 38 and 40 extend outwardly from the top of the slide block in contacting relationship and are each provided with an opening 41, and the openings in the two extensions are in registry and the bale is held together about the two sections of the slide block by means of a hollow rivet R that is flanged over the outer portions of the extensions or ears of the bale, see Fig. 3. The ring 8 at the end of the chain 7 passes through the hollow rivet and serves as a means to secure the chain to the slide block.

It is to be understood that if the passageway for the chain in the slide block is of sufficient tolerance with respect to the cross sectional diameter of the chain, the spring-pressed plunger in the slide block may be eliminated and the frictioning effect obtained solely by the close fit of the chain in the channel or, if desired, the chain may be loose in the channel and merely rest there by gravity and thus maintain the chain in any desired extended position.

While a chain has been referred to herein, it is also to be understood that flexible means other than a chain may well be utilized. For instance, synthetic materials that are flexible could be used in place of the chain 7 and/or the chain 10.

As illustrated in Fig. 1, the fastener 9 is attached to a trouser loop T and thus tethers the extension key chain to the article of clothing. The length of this chain 7 is such that it extends from the trouser loop down to a point adjacent the bottom of the pocket opening P in the trousers. The slide block, which is very ornamental, and may consist of contrasting colors due to the combination of the plastic body and the metal bale, is attached by means of the ring 8 to the end of the chain 7 and is free for slight swinging movement. The longer length of chain

10, which has the snap hook 12 thereon, is looped upwardly to the watch pocket W in the trousers and is attached to a watch or other article, not shown, and the other end of the chain is also looped upwardly and carries the key ring 11 thereon and which key ring may be disposed in the rear pocket B of the trousers. Obviously, the portion of the chain carrying the key ring and the key ring itself, of course, could be inserted in the side pocket P of the trousers.

When it is desired to extend the length of the chain 10 with respect to the tethered slide block 6, as illustrated in Fig. 5, it is assumed here that the slide block 6 is gripped by the fingers and is held stationary and that either portion of the chain opposite the slide block is pulled, it being seen from the dotted line indications in this figure that the chain 10 can be extended either to the left or right of the slide block by merely holding the slide block in the fingers and pulling on the chain.

With regard to the diagrammatic illustration of Fig. 6 of the drawings, it is assumed, as it was in Fig. 5, that the length of chain 7 is tethered by means of the fastener 9, which is secured to an article of clothing or the like, thus, by pulling either the end of the chain where the key ring 11 is attached, or the other end of the chain where the snap hook 12 is attached, and not holding the slide block 6, the tethered chain 7, which carries the slide block, will be moved at an angle with respect to the vertical such as shown in the dotted line positions, and the chain 10 may be extended from either side of the slide block depending upon which chain is pulled. The slide block will only swing as far as permitted by the length of the chain 7 when either end of the chain is pulled and then the chain will slide relative to the slide block and be extended to one of the dotted line positions of Fig. 6.

From the foregoing, it is believed quite clear that the chain 10 may be extended in one or two ways; namely, by holding the ornamental slide block 6 and sliding the chain through the block or merely leaving the slide block free and, in that instance, the tethered chain 7 will swing or move to a certain extent limited by the length of the chain 7 and then stop and, by further pulling on either end of the chain, the chain will slide relative to the slide block but, at one time, it will be seen that the chain 7 and the slide block 6 move or swing simultaneously with the chain 10.

The illustration of the use of the extension key chain in connection with trousers is not to be considered as limiting the use of the invention as one may want to use the extension key chain on a vest or other article of apparel. It has already been said that the key ring and the snap hook for the watch and any other such fastener may be substituted depending upon the requirements of the user.

What is claimed is:

1. An extension key and watch chain including a slide block, a suspension chain having a lower end permanently attached to the upper end of said slide block, the upper end of the chain having a fastener carried thereby for detachably connecting the chain with part of a garment and thereby suspend the chain and block for swinging movement to various positions and also allow the block to be bodily lifted together with the chain, said slide block having a passageway extending transversely therethrough, said passageway being of arcuate form throughout its length and circular in cross section and having its con-

caved side presented downwardly with opposite end portions thereof diverging downwardly, a chain of greater length than the first mentioned chain having a portion thereof at all times movably passing through the said passageway of the slide block, and securing means at each end of the last mentioned chain providing for attachment of articles thereto, the said longer chain being adapted to be slid longitudinally through the passageway in the slide block by pulling on either end of the said last mentioned chain or by moving the flexibly suspended slide block along the said last mentioned chain when the latter is held stationary.

15 2. An extension key and watch chain including a slide block, a suspension chain having a lower end permanently connected with the upper end of said slide block, a fastener at the upper end of said chain for detachably connecting the chain with part of a garment and thereby suspend the

20 chain and block for swinging movements to various positions and also allow the block to be bodily lifted together with the chain, said slide block having a passageway extending transversely therethrough, said passageway being longitudinally arcuate with its concaved side presented downwardly, the slide block being formed above

25 said passageway with a vertical socket having its lower end open and communicating with the passageway midway the length thereof, a spring pressed plunger slidable vertically in said socket and urged downwardly and having a rounded head at its lower end entering the passageway, a chain of greater length than the first chain having at all times a portion movably passing through the passageway and frictionally gripped by the head at the lower end of said plunger, and article holding members at opposite ends of the longer chain, said longer chain being slidable longitudinally through said passageway past said

30 plunger by pulling on either end of the said longer chain or by grasping the block and moving the block along the said chain when the said chain is held stationary.

35 4. A key chain as defined in and by claim 1 wherein the slide block is formed of two complementary sections, each section having an arcuate channel of semi-circular shape in cross section in the inner side thereof, and which channels when the sections are secured together form an arcuate passageway through the slide block for the longer chain, a securing strip disposed vertically about the block in close fitting engagement with the said complementary sections of the block and having ends forming ears extending upwardly

40 against each other, a hollow rivet passing through said ears and holding the same together, and a ring passing through said rivet and with which the lower end of the suspension chain is connected.

45 5. A key chain as defined in and by claim 1 wherein the slide block is formed of two complementary sections, each section having an arcuate channel of semi-circular shape in cross section in the inner side thereof, and which channels when the sections are secured together form an arcuate passageway through the slide block for the longer chain, a securing strip disposed vertically about the block in close fitting engagement with the said complementary sections of the block and having ends forming ears extending upwardly

50 against each other, a hollow rivet passing through said ears and holding the same together, and a ring passing through said rivet and with which the lower end of the suspension chain is connected.

55 6. A key chain as defined in and by claim 1 wherein the slide block is formed of two complementary sections, each section having an arcuate channel of semi-circular shape in cross section in the inner side thereof, and which channels when the sections are secured together form an arcuate passageway through the slide block for the longer chain, a securing strip disposed vertically about the block in close fitting engagement with the said complementary sections of the block and having ends forming ears extending upwardly

60 against each other, a hollow rivet passing through said ears and holding the same together, and a ring passing through said rivet and with which the lower end of the suspension chain is connected.
